UNITED STATES PATENT OFFICE.

CHARLES H. TWIST, OF NEW YORK, N. Y., ASSIGNOR OF ONE-HALF TO
WILLIAM T. MINOR, OF STAMFORD, CONNECTICUT.

RAILWAY-SWITCH PLATE.

SPECIFICATION forming part of Letters Patent No. 356,607, dated January 25, 1887.

Application filed November 14, 1885. Serial No. 182,833. (No model.)

To all whom it may concern:

Be it known that I, CHARLES H. TWIST, of the city of New York, in the county and State of New York; have invented certain new and useful Improvements in Railway - Switch Plates, of which the following is such a full, clear, concise, and exact description as will enable others skilled in the art to which my invention appertains to make and use the same, reference being had to the accompanying drawings, forming part of this specification.

It is a well-known fact that the rails of a railway contract and expand to a considerab'e extent, and that, owing to their connection with each other, the volume of contraction or expansion is carried from one rail to another, and oftentimes the continuity is uninterrupted for miles, and the lengthening or shortening of the track will of course be in accordance with the extent of the connected metallic surface. The most frequent, and practically the only, interruptions in a railway track, of the surface through or along which the expansion or contraction may be carried, are found at the switches, the rails of which not only have to be free from the ties, but also disconnected at their movable ends from the permanent track-rails. The result is that the expansion or contraction will culminate in the gain or loss at the switch-rails, and if in gain the switch-rails will be rendered practically immovable, while, on the other hand, the loss at such point will cause a considerable space to be left between the ends of the switch-rails and the ends of the adjacent track-rails. Such space will cause a jumping of the car-wheels in passing over this portion of the track, and the ends of both the switch-rails and the track-rails will become battered and injured to such an extent that they will frequently require replacing.

Heretofore railway-switches have been constructed with plates for the switch-rails to move upon, and these plates have been made to extend along on the ties, being connected at each end with the permanent track-rails. In such construction, however, the switch - rails being made to rest upon these plates, the cross-rods by which they are held together, so that one moves with the other, are necessarily above the level of the ties, and this renders that por-

tion of the track dangerous, because of the liability of a person's tripping while stepping from one tie to another. Moreover, the manufacture of such plates is very expensive, inasmuch as they must be broad enough to permit of the movement of the switch-rails upon them, and if made to taper from the movable end of the switch-rails, this requires an expensive cutting operation. Not only so, the manufacture of such switch-plates necessarily requires very heavy and expensive machinery, in order to roll and finish the metal so that it would be adapted to the purpose. For these and other reasons this form of switch-plate has not found sufficient favor to insure their adoption, except to a limited extent. Notwithstanding the efforts to overcome the difficulties heretofore experienced, as above mentioned, and the limited use of such switch-plates, the want of some practical and moderately-expensive means for connecting the track - rails where their continuity is broken by the switches has been felt, insomuch that it is a question of serious consideration among practical railway men.

The object of my invention is the construction of a switch or connecting plate which will be cheap to manufacture and easily applied, and by means of which connection is made between the track-rails which will relieve the switch-rails from the otherwise evil effects of the contraction and expansion, as hereinafter more fully described and claimed.

In the drawings, Figure 1 is a plan of a railway-switch and its connections with the main tracks. Fig. 2 is a vertical section of one side or rail of the track, showing one of the switch-rails and a portion of the abutting track-rails. This figure also shows the connecting-plate, which is made to pass under the ties upon which the switch-rail rests. Figs. 3 and 4 are respectively vertical sections of a portion of the connecting-plate, showing the relation of such plate to the ties and rails; and Figs. 5 and 6 are plans of Figs. 3 and 4, respectively, the lines *x x* and *y y* indicating where the sections represented by Figs. 3 and 4 are taken.

In these drawings, A A represent the fixed rails of the main track, B B the switch-rails, and C C the rails of the switch-tracks, or those tracks with which connection is made by the

movement of the switch; and D D represent the plates which connect the rails A A of the main track with the rails C C of the switch-tracks.

5 The rails of the several tracks other than the switch-rails are secured to the ties by spikes or otherwise, in the usual manner. The switch-rails B B are, however, made to rest upon the ties, without being fixed thereto, and 10 are connected together by cross-rods b b, so that the movement, by the operation of the switch of the cross-rods at the switch end, causes both rails to move at one time and connect with the different switch-tracks represented by the corresponding pairs of rails, C C. 15 In the construction of that portion of the track where the switches are located I place metallic plates D D under the ties, upon which the switch-rails rest. These plates are made 20 to pass above the ties upon which the track-rails are secured, being connected with the ends of such track-rails. The plates D D may be secured to the ties by spikes or otherwise. They are made either in one piece or in two or 25 more sections; but I prefer to make them in sections which are bolted or secured together, because in this way that part which rests under and is connected with the several rails of the respective switch-tracks may be made as 30 wide as it is desirable to have it, while the remaining portion can be as narrow as may be desired. In Fig. 1 the section of the plate which connects with the rails of the switch-tracks is shown as being made to extend entirely across the tracks, and as being connected 35 with all the rails, while in the same figure the dotted lines lengthwise of the track indicate a width which would simply admit of connections with those rails on a single side of the 40 tracks only.

To the section or sections having connection with the rails of the switch-track are secured the sections which extend underneath the ties upon which the switch-rails rest, either 45 by bolts or in any other desired manner. This section which lies underneath the ties is preferably of a uniform width and secured to the ties, being bent up so as to come above the tie at the opposite end, where it is connected 50 with the track-rail A; but a separate section may be used at such end, if desired. In Fig. 55 2 the plate is shown as being in one piece, which is bent up at both ends of the switch-rails and then made to extend under the track-rails, to which these ends are secured.

By making a part of the plate to extend under the ties upon which the switch-rails rest there is not the necessity for the use of an expensive metal, nor is there any need of a large expenditure in preparing the plates for use; and when the plates are placed in and connected with the track the switch-rails will slide upon the ties in the ordinary way, so that the cross-rods will not be brought above the ties and interfere with passage along the track. 60

I am aware that it has been proposed to counteract the expansion of the rails of the main track by means of stay-rails placed under the road-bed beneath the switch-rails, such stay-rails being bolted to the main rails for the 70 purpose of arresting the longitudinal movement thereof and to form a solid bearing and anchorage at the point of attachment of the main rails with the stay-rails; but the interposition of such stay-rails differs from my invention in that I do not place my plates under the road-bed or seek to arrest the contractile and expansive forces of the main rails by solid bearings or anchorage, but to divert the course of the contraction and expansion 80 across the space occupied by the switch-rails; hence I do not wish to be understood as claiming stay-rails placed under the road-bed beneath the switch-rails and serving to arrest or stay the contractile and expansive forces. 85

Having thus described my invention, what I claim as new, and desire to secure by Letters Patent, is—

1. In a switch for railways, a metallic plate or plates made to pass directly beneath the 90 ties upon which the switch-rails rest and above the road-bed and to pass above the ties at the opposite ends of the switch-rails, said plate or plates being secured at such opposite ends to the track-rails, substantially as and for the 95 purpose set forth.

2. In a switch for railways, a metallic plate or plates composed of two or more sections secured together, said plates being made to pass directly beneath the ties upon which the 100 switch-rails rest above the road-bed and to pass above the ties at the opposite ends of the switch-rails, the same being secured at such opposite ends to the track-rails, substantially as and for the purpose set forth.
